UNITED STATES PATENT OFFICE.

ANDREW A. BOMBACH, OF LORAIN, OHIO.

SHIP-PROTECTOR.

1,262,439.

Specification of Letters Patent.

Patented Apr. 9, 1918.

Application filed July 3, 1917. Serial No. 178,448.

To all whom it may concern:

Be it known that I, ANDREW A. BOMBACH, a citizen of the United States, residing at Lorain, in the county of Lorain and State of Ohio, have invented new and useful Improvements in Ship-Protectors, of which the following is a specification.

This invention relates to fenders or protectors for sea-going vessels.

10 The object of the present invention is to provide means whereby a vessel may be protected from contact with mines or torpedoes or other destructive devices, the protecting means being secured to the vessel and spaced therefrom, in order that dangerous objects may be prevented from coming in contact with the hull.

15 A further object of the invention is to provide a protecting means secured to the bow 20 of the vessel, which is capable of being moved to an operative or an inoperative position, so that when it is not desired to use the same, it may be raised from the water so as not to interfere with the progress of 25 the vessel or the docking thereof.

20 A still further object is to provide independent fenders secured to the hull of the vessel and spaced therefrom so as to provide a substantially continuous protecting wall 30 around the outside of the hull for the purpose of preventing contact of any dangerous object with the said hull and at the same time providing for the replacing of worn or 35 injured fenders without the necessity of disturbing the others, the independent fenders being detachably connected to strengthen the protecting wall.

35 Still another object of the invention is to provide means whereby the independent 40 fenders of protectors may be simultaneously raised to an inoperative position when desired or quickly and readily lowered into position to effectually protect the vessel against danger.

45 With these and other objects in view the invention consists of the following novel combination and arrangement of parts hereinafter more fully described, illustrated in the accompanying drawings and pointed out 50 in the appended claims.

In the drawings:

Figure 1 is a side elevation of a vessel equipped with the invention and illustrating the forward fender or scoop in an op-

erative position in full lines and in an inoperative position in dotted lines; 55

Fig. 2 is a plan view of the same with the dotted line position omitted;

Fig. 3 is a transverse sectional view through the hull of the vessel showing the 60 relation of the side fenders to the hull;

Fig. 4 is a detailed sectional view on the line 4-4 of Fig. 2, this section being taken through the forward fender and a portion of the bow of the vessel; 65

Fig. 5 is a detailed perspective view of one of the independent sections of the side fenders; and

Fig. 6 is a detailed view illustrating the manner of connecting the independent 70 fender sections.

Referring in detail to the drawings, A indicates the hull of the vessel, which may be of any type. To the forward end of the hull there is pivotally secured a fender or 75 scoop 10, this fender including a series of spaced curved bars 11, which are pointed at their forward ends as indicated at 12. These bars are secured at their rear ends to a transversely disposed member 13 and have 80 their forward or pointed ends spaced apart as indicated at 14. The transverse member has secured thereto spaced arms 15, which are pivotally secured to the forward ends of supporting frames 16. These frames comprise forwardly extending substantially horizontal members 17, which are secured at one end to the bow of the vessel and are supported at their opposite ends by means of inclined braces 18 which in turn are 85 mounted upon stanchions 19 secured to the forward deck.

This pivotal mounting of the fender or 90 scoop 10 enables it to be lowered into the water when desired or to be raised from contact therewith. In order to accomplish this raising or lowering the transverse member 13 carries an arm 20, which has mounted upon its free end a pulley 21. Secured to the bow of the vessel is a sheave or pulley 22 and the rope or cable 23 is reaved through this pulley in order that the fender may be 95 operated from the deck of the vessel. To facilitate this operation there is mounted upon the forward deck 23 a windlass 25 of 100 any suitable construction, which may be either hand or power operated. Suitable stay or brace rods 26 may be secured to the

supporting frames and the hull for the purpose of rendering these frames rigid. In addition thereto, the frames may be provided with stays in the form of chains or cables 22, these stays passing through the hull and being adjustably secured to the forward deck by means of the bifurcated members or bits 28. By adjusting the chains 27 upon the bits 28, the depth of the fender may be regulated, so that it will be unnecessary to adjust the same each time the fender is raised or lowered, in order to reach the proper depth.

In order to protect the sides of the hull, there is provided a series of independent sections, which coöperate to form a substantially continuous outer wall spaced from the wall of the vessel. Each of these sections comprises a substantially horizontal arm 29, which is hinged to a bracket carried by the hull as shown at 30. Carried by the outer end of the frame 29 is a substantially vertically disposed grate like element 31, the fingers 32 of which are disposed equally upon both sides of the arms 29, these fingers being equally spaced apart and coöperating with the fingers of the adjacent grate like elements to provide a substantially continuous wall, each of the elements 31 being detachably connected by means of a U-shaped bolt 31. The fenders just described are secured to the hull of the vessel at a point above or near the water line thereof and the fingers 32 are of a sufficient length to extend even with or below the bottom of the hull to effectually prevent contact therewith of any dangerous objects. By forming these fenders in separate sections the said sections may be easily replaced in event of damage thereto without the necessity of renewing the entire protecting means.

Mounted upon the deck of the vessel are shafts 35, the said shafts being mounted in bearings 36 located along each of the side rails of the vessel and being driven by suitable motors 27. Connected to the horizontal arms 29 of each of the side fenders are chains or cables 38, which are adapted to be wound upon the shaft 35 for the purpose of simultaneously raising or lowering the protectors. This is especially useful when the vessel is warped, the raising of the fenders permitting of a close positioning of the vessel when it is desired to load or un-

load the same. It is of course understood that if desired certain of the fenders or protectors may be raised by hand.

In order to provide for the raising and lowering of the fenders which are mounted upon the side bow of the vessel, there is provided a countershaft 39, which is driven from shaft 35 by gearing 40, so that the valve fenders will be raised in unison with those located at the sides of the hub.

The fenders or protectors which are located upon each side of the extreme prow of the vessel are provided with an independent motor 41, which is adapted to have wound thereon the chains or cables 38.

By making the forward fender adjustable, the same may be raised from the water when the vessel is under way and quickly lowered in position when reaching the danger zone, or when sighting any possible ship. This fender is also capable of use in lifting objects from the water and may be found advantageous in the rescuing of persons from drowning.

Additional braces or supporting cables 45 are secured to the outer ends of certain 80 of the fenders and to the brackets of the adjacent fender for the purpose of supporting the same and taking the strain from the adjusting cables.

It is believed that from the foregoing the construction, operation and many advantages of the invention will be apparent and the right is reserved to make such changes in the construction as will fall within the scope of the appended claims.

Having described the invention, what is claimed is:

The combination with a vessel, of a series of independent fender sections, said sections each comprising a normal horizontally disposed arm hingedly secured to the hull of the vessel and extending laterally therefrom, a transversely disposed arm secured intermediate its ends to the first mentioned arm and disposed at right angles thereto, 100 downwardly extending spaced fingers carried by the transversely disposed arm and means for removably securing the sections together to form a grate like protector wall spaced from the hull of the vessel.

In testimony whereof I affix my signature.

ANDREW A. BOMBACH.
